CLAIM

The ornamental design for a transfer door enabling the docking of a container for the transfer of goods, as shown and described.

DESCRIPTION

FIG. 1.1 is a right side view of the design;

FIG. 1.2 is a bottom view thereof;

FIG. 1.3 is a top view thereof;

FIG. 1.4 is a back side perspective view thereof;

FIG. 1.5 is a front side perspective view thereof;

FIG. 1.6 is a front view thereof; and

FIG. 1.7 is a back view thereof.

(Continued)

The broken lines in FIGS. 1.1-1.7 illustrate unclaimed subject matter and do not form any part of the claimed design.
